UNITED STATES PATENT OFFICE.

ALEXANDER H. WOOD, OF KILDAV, KENTUCKY, ASSIGNOR TO WOOD EQUIPMENT COMPANY, OF CHICAGO, ILLINOIS, A CORPORATION OF ILLINOIS.

RAILWAY-DUMP.

1,325,181.

Specification of Letters Patent. Patented Dec. 16, 1919.

Application filed April 7, 1917. Serial No. 160,427.

To all whom it may concern:

Be it known that I, ALEXANDER H. WOOD, a citizen of the United States, residing at Kildav, in the county of Harlan and State 5 of Kentucky, have invented a new and useful Improvement in Railway - Dumps, of which the following is a specification, reference being had to the accompanying drawing.

10 My improvement relates particularly to railway dumps which receive loaded cars upon one track and discharge said cars, when empty, from the same end of the dump and upon another track, the movement of 15 the cars toward and from the dump being usually by gravity.

The object of the invention is to provide an adjacent dumping structure by means of which loaded cars may quickly enter the dump, discharge their loads, and move out upon the discharge or return track.

In the accompanying drawings,

Figure 1 is a plan of a structure embodying my improvement, portions being omitted;

25 Fig. 2 is a side elevation of the same structure, portions being broken away;

Fig. 3 is a section on the line, 3—3, of Fig. 1, looking toward the left;

30 Fig. 4 is a section on the line, 3—3, of Fig. 1, looking toward the right;

Fig. 5 is a detail elevation;

Fig. 6 is a view similar to Fig. 3, showing mechanism for shifting the platform;

Fig. 7 is a detail upright section.

35 Referring to said drawings, A is an understructure such as is ordinarily used for supporting car dumping mechanism, excepting that in the present case this understructure is modified to meet specific requirements.

40 On the understructure, A, is a shiftable platform, B. At one end (the left hand end in the drawing), said platform is supported by a swivel structure having an upright axis B¹, and resting on the understructure, A.

45 At its free end (the right hand end in the drawing), said platform is supported by wheels, B² which have axes, parallel to the length of said platform and which wheels rest on a track rail, A¹, on the understructure, A, said rail being curved with the pivot, B¹, for a center. Intermediate its ends, said platform is provided with another pair of wheels, B³, resting on a rail, A², which is parallel to the rail, A¹, and

50 55 also supported by the structure, A. The platform may be turned on its pivot, the

free end of the platform traversing the length of the rail, A¹.

A car track, C, leads from the right to the free or right hand end of the platform, 60 the latter being in the position shown in Fig. 1, the position in which loaded cars are to be received from the track for dumping. For convenience in description this position will be called the "receiving" position, 65 while the position on the other end of the rail, A¹, is called the "discharge" position.

A car track, D, leads from the structure, A, beside the track, C, and in position to register with the platform, B, when the latter has been turned into the discharge position.

The tracks, C and D, are placed at proper elevations to register with the track in the rotary tubular frame supported on the platform, B, as hereinafter described.

The rails, A¹, and A², are inclined, the lower position being adjacent the track, D, in order that the free end of the platform may be lower when it is opposite the track, 80 D, than when it is opposite the track, C. This brings the two ends of the platform to the same level when the platform is aligned with the track, C, and brings the free end of the platform lower when the platform is 85 aligned with the track, D. The purpose of this latter feature is to facilitate discharge of empty cars from the dump outward upon the track, D. A stop post, E, limits the

movement of the platform away from the 90 track, D; and a similar stop post, E¹, limits the movement of the platform in the opposite direction. A cable or chain, E², is attached to the platform adjacent the post, E, and leads horizontally and at right angles 95 from the platform over a sheave, E³, downward to a counterweight, E⁴. The counterweight thus suspended is to be made sufficient to draw the platform, when the latter supports no cars, toward the sheave, E³, 100 until the platform meets the stop, E. But while said counterweight is to be heavy enough to perform the function just described, it is to be light enough to permit easy movement of the platform away from 105 the post, E, when the platform supports a trip of cars. These several parts are preferably so proportioned as to permit the platform, when loaded with a trip of cars to overcome the counterweight and move over the 110 inclined rails, A¹ and A², until the platform meets the stop post, E¹. The movement of

the platform away from the post, E, may be facilitated by applying power to the wheel, E⁶, on the shaft, E⁵, of the sheave, E³, to turn the latter so as to lift the counterweight.

5 In Fig. 6 the cable, E², and the counterweight, E⁴, are omitted, and a cable, E⁷, is attached to the adjacent portion of the platform, B, and then around the sheave, E³, and thence beneath the platform and beneath a 10 sheave, E⁸, adjacent the stop post, E¹, and thence over said sheave into engagement with the adjacent edge of the platform. By turning the wheel, E⁶, in the appropriate direction, the platform is drawn away from 15 the post, E, and to the post, E¹; and by rotating said wheel in the opposite direction, the platform is returned to its position against the post, E.

For holding the platform in the receiving 20 position, a hook, E⁹, is hinged to the edge of the body, B, at E¹⁰, in position to extend over a horizontal stud, E¹¹, on the right hand side of the post, E, said hook having at its outer end an oblique face, E¹², adapted to slide 25 over the stud, E¹¹, when the platform, B, moves against the post, E, whereby the engagement of said hook is made automatic. For holding the platform in the discharge position, against the action of the counter- 30 weight, a hook, E⁹, is placed at the opposite side of the platform to engage a stud, E¹¹, on the post, E¹.

On the platform, B, are wheels, F, arranged with their axes on two lines which 35 are parallel to each other and to the length of the platform, and said wheels are supported upon bearings, F¹. Said wheels make supports for a tubular cylindrical frame, G, formed of longitudinal bars, G¹, and trans- 40 verse rings, G², the latter resting on the wheels, F. Within said tubular frame are longitudinal track rails, G³, which are adapted to register with the rails of the track, C, when the platform, B, is in alinement with 45 that track and to register with the rails of the track, D, when the platform is in alinement with that track. Above the rails, G³, are upper rails, G⁴, which are above the path of the wheels, H¹, of the car, H. Said four 50 rails are adapted to hold the car during the rotation of the tubular frame, G, for inverting the car to discharge its contents by gravity. For further details concerning such a 55 rotary tubular dumping frame, reference is made to Letters Patent of the United States, No. 1,204,527, granted to me November 4, 1916. The mechanism for rotating said tubular frame may be of any suitable form. For this purpose, the drawings show the wheels, 60 F, at one side of said tubular frame mounted on a continuous shaft, F², and an electric motor, I, mounted upon the platform, B, and connected with said shaft by gears, I¹, I², I³ and I⁴ (Fig. 7).

65 On the structure, A, at the pivot end of

the platform is a buffer, J, of any suitable form and standing high enough to be engaged by cars which tend to move through the tubular frame, G.

In operation, the platform, B, is put into 70 the receiving position, in alinement with the track, C. Any number of loaded cars suited to the length of the tubular frame, G, ordinarily a trip of six or eight cars, are now moved over the track, C, into said tubular 75 frame. This may be done by gravity, the track, C, being inclined toward the dump. When the cars enter said tube by gravity, the buffer, J, limits their movement. As soon as the cars are at rest in the tube, the motor, 80 I, is set into action to rotate the tubular frame for the discharging of the loads from the cars. Or the rotation of the tube may be deferred until the platform has been moved to the discharge position. In some 85 situations, this may be desirable because then the weight of the loads in the cars will help to move the platform from the receiving position over the inclined rails, A¹ and A², 90 into the discharge position, the counterweight, E⁴, having opposed to it the weight of the loads in said cars.

Before the platform is shifted out of the receiving position, the cars should be secured 95 against movement toward the discharge end of the tube. This can be done by means of suitable blocks or similar devices placed in front of a portion of the car wheels. When the platform stands in the discharge position 100 and the cars are empty and the tubular frame has been righted so that the rails, G³, of the tubular frame, G, register with the rails of the track, D, said blocking is removed to allow said cars to run by gravity 105 out of the tubular frame and over the track, D.

The hook, E⁹, (if it is used) is now released to allow the counterweight to draw the platform back into the receiving position 110 to receive another trip of cars.

I claim as my invention,

In an apparatus of the nature described, two car tracks located and terminating side-by-side, at different elevations, an understructure located adjacent the ends of said tracks and having an inclined track transverse to said two tracks, a platform supported upon said understructure track and swiveled at one end and turnable on said swivel 115 to bring the free end of said platform alternately opposite said car tracks, and means on said platform for receiving a car from one of said tracks and supporting said car 120 while its load is being discharged substantially as described.

In testimony whereof I have signed my name this tenth day of March, in the year one thousand nine hundred and seventeen.

ALEXANDER H. WOOD.
